UNITED STATES PATENT OFFICE.

GUSTAV R. RODDY, OF MILWAUKEE, WISCONSIN, ASSIGNOR TO CHAIN BELT COMPANY, OF MILWAUKEE, WISCONSIN, A CORPORATION OF WISCONSIN.

FLUME SCREEN WITH INDICATING DEVICE.

Application filed October 3, 1924. Serial No. 741,429.

To all whom it may concern:

Be it known that I, GUSTAV R. RODDY, a citizen of the United States, residing at Milwaukee, in the county of Milwaukee and 5 State of Wisconsin, have invented certain new and useful Improvements in Flume Screens with Indicating Devices, of which the following is a specification.

My invention relates to liquid screening apparatus such as is used for taking from sewage, or water to be used for industrial purposes, the coarser material that may be carried thereby; and it is particularly adapted for use in apparatus of this nature in 10 which the screen is in the form of an endless traveling belt made up of filter or screen sections supported upon and carried by sprocket chains, and where the screen stands vertically, the opposite screen surfaces moving in vertical planes and at right angles to the path of the flowing liquid, one traveling downward, and the other upward.

In the accompanying drawings:

Figure 1 is a side elevation of a liquid screen embodying my invention, with certain parts broken away, and other parts, that are not necessary for an illustration of the invention, omitted.

Fig. 2 is an end view of the screen illustrated in Fig. 1, certain parts being broken away and omitted, and other parts being represented in vertical section.

Fig. 3 is a vertical sectional view on a scale much larger than Figs. 1 and 2 illustrating one end of the supporting shaft for the foot wheels, and associated means for preventing undesirable flow of unscreened water at this point.

Fig. 4 is a sectional view taken on the line 40 IV—IV of Fig. 3.

Fig. 5 is a detail view showing an elevation of means for amplifying the movements of the indicator.

Fig. 6 is an end view of the indicator 45 represented in Fig. 5.

Fig. 7 is a sectional view taken on the line VII—VII of Fig. 5.

Referring to the drawings A indicates the supporting and guiding framework of the 50 apparatus, B, the large head sprocket wheels, C, the large foot sprocket wheels, and F the sprocket chains that carry the screen sections E and engage with the said sprocket wheels B and C. The head wheels B have connected 55 with them adjusting mechanism D, which,

so far as this invention is concerned, may be of any usual or preferred form. The lower or foot wheels, which, when the apparatus is in use are immersed in the liquid to be screened, extend into a boot G, that encases them at the sides and bottom, and is supported by the framework A. Directly below the screen, where it makes the turn about the foot wheels C, and extending from one end wall 2 of the boot to the other, is located a curved boot plate H. The screen sections E are formed with lips I that assist in retaining the material collected from the liquid on the uprun of the screen.

The parts thus far described are common and well known in the art. In the use of a liquid screen such as described, it is customary to adjust the upper or head wheels B by means of the mechanism D so as to give the proper tightness to the sprocket 70 chains F. These chains, however, sooner or later wear at their joints, with the result that they sag and fall away somewhat from the lower sprocket wheels, which wheels it has been customary to support upon a shaft c 75 that is fixedly mounted in or relative to the boot G. As a result of the looseness of the chains due to use and wear, the lips I of the screen sections travel undesirably close to the boot plate H, or even drag along the surface thereof. But it cannot always be ascertained when this undesirable condition occurs, owing to the fact that the foot wheels and lower portions of the screen are submerged, and so it frequently happens that 80 the upper sprocket wheels are not adjusted to take up the slack in the chains until the apparatus has run for a considerable period of time under the undesirable conditions referred to.

My invention has for its object to provide automatic indicating means that are adapted to inform the one operating the apparatus whenever the chains F are properly adjusted, as well as when they are stretched or become 85 so worn as to interfere with the most desirable working of the apparatus, and I will now describe one form of such indicating mechanism.

In the end walls 2 of the boot are formed 100 vertically elongated openings or slots 1 through which extend the ends of the shaft c on which turn the lower or foot sprocket wheels C. In the end portions of this shaft are formed flat seats 18 against which rest 110

the edges of keeper plates 3, located just inside the end walls of the boot. Each keeper plate is secured, by bolts 5, to a follower plate 4 somewhat larger than the keeper plate, and through which is a hole 14 for the passage of the shaft *c*. The plates 3 and 4, thus united, are located in slideways 6 secured to the inner faces of the end walls of the boot, in which they are free to move 10 along vertical lines. The keeper plates 3, being secured fast to the follower plates 4, and the latter in turn held in place by the slideways 6, prevent rotation of the shaft *c* in its supports, but permit it to move vertically to the extent allowed by the slots 1. The plates 3 and 4 serve also to cover the slots 1 and prevent any appreciable flow of liquid through them during the operation of the apparatus. The slots 1 need not be 20 long, as a vertical movement of less than one inch is all that ordinarily should be allowed the shaft *c*, due to looseness, wear or stretching of parts, before adjustments of the head wheels *B* should be made. 25

7 indicates a collar secured fast to the shaft *c*, by a set screw 8 just inside the hub of one of the wheels *C*. Seated in a screw-threaded aperture provided therefor in the collar 7 is the lower threaded end of a rod 30 9 that extends upward to a position where its upper end may be conveniently observed. At such upper end it is provided with a pointer 11 that moves across the face of a dial plate 12, suitably supported. The rod 35 9 passes through one or more guides 10 by which it is suitably held and maintained in position. The operation of my invention may be understood from the foregoing description 40 taken in connection with the drawings.

When the apparatus is set up for use the shaft *c* should occupy the upper portion of the slots 1. As the chains wear and stretch through use the shaft falls, and its movement downward is indicated by the pointer traveling over the face of the dial 12, and thus gives the warning to the operator when the head wheels should be adjusted. 45

When the indicator is constructed and arranged as described the movements of the pointer 11 are short and might fail to attract the attention of the attendant in charge of the operation of the machine. I have, therefore, in Figs. 5, 6 and 7 illustrated means for amplifying the movement of the indicator. 50

Referring to these views 15 indicates an arm at the upper end of the rod 9, at the end of which is secured a gear rack 16 in mesh with which is a pinion 17, the shaft 18 of which carries a pointer 11' that moves, in a curved part, across the face of a dial 12'. 55

I have illustrated my invention by means of a visible indicator, consisting of a pointer

moving across the face of a dial, and while this is a practical and perhaps the most obvious form of the invention it is not the only practical one, and its choice and illustration is therefore to be considered as typical of any indicating device, which might be substituted for a pointer and dial and serve as the equivalent thereof in giving the desired information or warning to the one in charge of the apparatus. 75

The indicating apparatus is operated by the movements of some part of the screen apparatus due to wear or slackness from use. In the embodiment of the invention here shown it is the shaft *c* and the submerged parts which it supports that directly give motion to the indicating device, this part falling by gravity as the chains *F* stretch or wear at the joints; but my invention is not limited to the particular arrangement shown. It may be embodied in various arrangements of apparatus, for instance, where the shaft for the lower or foot wheels is supported in fixed bearings, and where the chains as they pass the lower wheels tend to sag or fall away therefrom, due to the chains becoming slack from wear or stretching; and the indicator may be operated by reason of such sagging of the chains. In another application signed by me of even date herewith, I illustrate and claim apparatus such as just referred to, 95

What I claim is:

1. In a liquid screening apparatus, the combination with an endless screen and means for supporting and driving the same, of an indicating device controlled by those movements of the screen due to the wear or adjustment of parts. 100
2. In a liquid screening apparatus, the combination with an endless screen and means for supporting and driving the same, of an indicating device controlled by movements of those portions of the screen which are submerged due to the wear or adjustment of parts. 105
3. In a liquid screening apparatus, the combination with an endless screen and means for supporting and driving the same, of a device for indicating the movements of the screen due to the wear of its parts, and connections for operating the indicating device arranged to be operated by the screen apparatus as it moves in a peculiar path or manner incident to the wear or adjustment of parts. 110
4. In a liquid screening apparatus, the combination with an endless screen and means for supporting and driving the same, parts of the screen apparatus being free to sag by action of gravity as parts wear, of an indicating device, and means for controlling the indicating device arranged to be operated by reason of the aforesaid sag of parts of the screen apparatus. 115
5. In a liquid screening apparatus, the combination with an endless screen and means for supporting and driving the same, of an indicating device, and means for controlling the indicating device arranged to be operated by reason of the aforesaid sag of parts of the screen apparatus. 120
6. In a liquid screening apparatus, the combination with an endless screen and means for supporting and driving the same, of an indicating device, and means for controlling the indicating device arranged to be operated by reason of the aforesaid sag of parts of the screen apparatus. 125
7. In a liquid screening apparatus, the combination with an endless screen and means for supporting and driving the same, of an indicating device, and means for controlling the indicating device arranged to be operated by reason of the aforesaid sag of parts of the screen apparatus. 130

5. In a liquid screening apparatus, the combination with an endless screen, head and foot wheels which support the same, adjusting mechanism for the head wheels, and
5 supports for the foot wheels which permit them to fall as the chains stretch and wear, of an indicating device, and connections between the indicating device and the foot wheels arranged to indicate the position of
10 the foot wheels.

6. In a liquid screening apparatus, the combination of an endless screen, head and foot wheels which support the same, adjusting mechanism for the screen, a shaft on
15 which the foot wheels are supported mounted so as to be free to fall as the endless screen wears and stretches, a rod connected with the shaft so as to move up and down as the shaft falls, and an indicating device controlled by
20 the rod.

7. The combination stated in claim 6, including means located between the rod and indicating device for increasing the amplitude of the movement of the latter relative to that of the rod. 25

8. In a liquid screening apparatus, the combination of an endless screen, head and foot wheels which support the same, a boot in which the foot wheels turn, the end walls of which are slotted, a shaft on which the foot 30 wheels are supported the ends of which lie in the slots in the end walls of the boot, plates secured to the shaft covering the said slots, guides for the plates to prevent the turning of the shaft to permit it to move 35 vertically, a rod connected with the shaft, and indicating means operated by the shaft to indicate the vertical movements of the shaft.

GUSTAV R. RODDY.
